TANGENT ADJUSTING MEANS

Adolph Langsner, Chicago, Ill., assignor to Eugene Dietzgen Co., Chicago, Ill., a corporation of Delaware

Application April 16, 1938, Serial No. 202,426

38 Claims. (Cl. 33—72)

My invention relates in general to precision adjusting devices and has more particular reference to means for adjusting transits, levels and similar instruments used in surveying, the present application comprising a continuation in part of my copending application for United States Letters Patent on improvements in Transits, Serial No. 757,849, filed December 17, 1934.

An important object of my present invention resides in providing an adjustable support, as in a transit, comprising frame elements interconnected for relative angular movement and including mechanism, such as tangent adjusting means, for adjusting the relative angularity of the frame elements and comprising parts designed to cooperate in excluding dirt and other foreign matter from the adjusting mechanism; a further object being to form the component parts to facilitate assembly thereof, to strengthen the same against mechanical damage, and to impart a pleasing appearance in the assembled device.

Another important object is to provide tangent adjusting means for angularly adjustable frames, comprising adjustable pintles on one frame and a projecting finger on the other, wherein the pintles are carried in a mounting formed to provide a chamber in position to receive the projecting finger whereby the tangent adjusting mechanism may cooperate with the projecting finger entirely within the housing in order to enclose and protect the parts from mechanical damage and deleterious foreign matter, such as atmospheric dirt and moisture; a further object being to arrange the projecting finger in position extending into the housing through a lateral opening therein and to provide, in association with the projecting finger, means forming a cover for closing the opening at all times, while permitting movement of the projecting finger within the housing in response to operation of the pintles.

Another object is to form a tangent adjusting pindle mounting as a housing for the exclusion of deleterious foreign matter, and to protect the same from mechanical damage.

Another important object is to mount the adjusting pintles in the opposite ends of an elongated shell forming an enclosing housing, the housing having an opening in a side thereof through which the finger may extend into the housing, said opening having a defining edge forming a flat seat, and the finger having associated means forming a cover in position to engage the seat and seal up the opening. Another object is to curve the seat on the arc of a circle

and provide a correspondingly curved cover. A further object is to interpose a sealing gasket between the seat and the cover.

Another important object is to arrange the pindle mounting housing as an integral part of one of the relatively adjustable frames. A further object is to arrange the cover as an integral part of one of the relatively adjustable frames. A still further object is to form the seat with a socket mounting therein for the projecting finger. Yet another object is to provide for removably mounting the finger, as by threading the same in the socket. A further object is to form the finger with a hardened insert forming a pindle bearing. Another object is to form the finger mount as a cover for the pindle housing.

Another object is to arrange tangent adjusting means for angularly adjustable frames, comprising cooperating pindle and finger elements, wherein one of the elements is mounted on projecting portions of a clamp adapted to be secured in any desired angular relationship on one of the adjustable frames, the other element being carried by the other frame; a further object being to arrange the clamp with operable means for securing the same in clamped position in a desired angular relationship on its associated frame, the operable means extending in the projecting portions of the clamp adjacent the clamp mounted element of the tangent adjusting assembly, so that the clamp and the tangent adjusting means may be operated from closely adjacent positions in the assembly.

Another important object is to form the pindle mounting and housing means as an integral part of a clamp.

Another important object is to mount the finger element on a clamp adapted to be secured on one relatively adjustable frame, with the pindle housing on the other frame.

Another important object is to provide an improved manually-operable head for actuating stems in tangent adjusting means, clamps and the like having movable stems supported in usually sleeve-like stem mounts, by forming the head with a cylindrical socket for receiving a cylindrical portion of the stem mount and forming therewith a substantial bearing for supporting the head on the stem mount to protect and enclose the end of the stem projecting from the stem mount and to prevent stem bending as a result of forces applied accidentally on the actuating head.

Another important object is to provide, in de-

5 vices having an adjustable stem or pintle extending in a sleeve with an end of the stem projecting outwardly of the sleeve, the combination, with the stem and sleeve, of a manually operable head on the projecting end of the stem for actuating the stem in the sleeve, the head having a socket snugly embracing the end of the sleeve to an appreciable extent whereby to support the head on the sleeve substantially 10 against screw bending movement, and thus protect the stem from mechanical damage as from screw bending forces applied accidentally on said head.

15 A further object is to provide means for sealing a tangent clamp against ingress of deleterious matter to the bearing means by which the clamp is mounted on its associated frame element.

20 Another object is to provide an improved dust, moisture and dirt-proof tangent clamp construction embodying in combination an upper and a lower clamp arrangement of the general character employed in transits, wherein both clamps are adapted to be adjustably clamped on a common 25 intermediate frame, one clamp affording tangent adjustment in cooperation with a support frame carrying the intermediate frame, and the other clamp affording tangent adjustment in association with a mounting frame supported 30 on the intermediate frame and carrying a sighting device.

Another object is to provide an improved tangent clamp construction for adjusting a sighting device tilting about a horizontal axis.

35 Another object is to provide an improved tangent clamp construction for adjusting a telescope rotatably about a vertical axis.

Another object is to provide improved tangent 40 adjusting mechanism structure adapted for use in association with the compass plate of transits; for use in association with the leveling frame of transits and the structure supported thereon; for use in adjusting the tilt of sighting devices; and for use in levels and the like.

45 These and numerous other objects, advantages and inherent functions of the invention will become apparent as the same is more fully understood from the following description, which, taken in connection with the accompanying drawings, discloses preferred embodiments of the invention.

Referring to the drawings,

Figure 1 is a perspective view of a transit comprising tangent clamp structures and tangent 55 adjusting mechanism embodying my present invention;

Figure 2 is an enlarged sectional view taken substantially along line 2—2 in Figure 1;

60 Figures 3, 4 and 5 are perspective views of tangent clamps contained in the transit assembly shown in Figure 1;

Figure 6 is a fragmentary sectional view taken substantially along the line 6—6 in Figures 3, 4 and 5;

65 Figures 7, 8 and 9 are sectional views, respectively, taken substantially along the lines 7—7 in Figures 3, 4, 5 and 8, along the lines 8—8 in Figures 1, 2, 3 and 5, and along the lines 9—9 in Figures 1, 2 and 4;

70 Figure 10 is a perspective view showing a modified arrangement of the tangent adjusting means illustrated in Figures 4 and 9;

Figure 11 is a perspective view, partially in 75 section, showing a modified arrangement of the

tangent adjusting means shown in Figures 3, 7 and 8;

Figure 12 is a sectional view taken along the line 12—12 in Figure 11; and

Figures 13 and 14 are perspective views of tangent clamp and adjusting means embodying my invention as applied in a level.

To illustrate my invention, I have shown precision measuring instruments for use in surveying, and comprising tangent clamp structures 10 and tangent adjusting mechanism embodying the features of my present invention. It will be obvious, however, that the invention is not necessarily restricted to clamps and adjusting means embodied specifically in surveying instruments. On the contrary, many features of the present invention may be utilized to advantage in any assembly of relatively movable frames requiring relative angular adjustment. For the purpose of exemplification, however, I have illustrated the invention as the same may be embodied in transits, levels and other surveying instruments, and to this end I have shown a transit 21 and a level 23, respectively, in Figures 1 and 13 of the drawings. The transit and 20 level both comprise adjustable support means for mounting a sighting device, which, in each of the illustrated embodiments, comprises a telescope 25, and for accurately adjusting the angularity of the sighting device in order to train 30 the same upon sighted objects.

The transit 21, of course, provides for adjusting the sighting device to accurately sighted position and is formed to measure and indicate the adjusted position of the sighting device in 35 terms of its displacement from a predetermined datum position.

Both the transit and the level comprise a support element or base 27 provided preferably with means 28 for mounting the same as on a supporting tripod (not shown). The support element 27 comprises a leveling screw plate on which is tiltably mounted, as by means of a ball and socket connection 29, a tilting frame 31 having a sleeve-like portion 33 connected at one 40 end on the base 27 by means of the ball and socket connection 29. The frame 31 has a plurality of arms 35 preferably integral with the sleeve portion 33 and extending radially outwardly thereof in position carrying leveling screws 37. These leveling screws are threaded 45 in openings formed in the extremities of the arms 35 which are preferably split at said openings, as at 39, and provided with clamping screws 41 to adjust tightness of the split arm portions 50 on the leveling screws.

The leveling screws comprise threaded stems and project above and below the arms 35, the stems being formed at their lower ends with balls 43 adapted for reception in sockets 45 formed on 60 or carried by the base 27 at or near the peripheral edge thereof. The sockets 45 preferably comprise cup-shaped elements having their bottoms secured to the base 27, the sides of the cup-shaped elements being peened at their upper edges 65 around the balls 43 in order to secure the same in these sockets.

The leveling screws carry substantially disk-like portions 47 which extend outwardly of the screws intermediate the base 27 and the frame 70 31, and the peripheral edges of the disks 47 are or may be knurled as shown to facilitate manipulation of the same in adjusting the tilted relationship of the frame 31 on the base plate 27.

Dust caps 49, preferably comprising spun 75

sheet-metal shells, may be secured on the arms 35 in position to enclose the upper projecting ends of the screws 37.

The sleeve-like portion 33 of the frame 31 provides a journal for rotatably supporting means on which the sighting device 25 is mounted, and it will be understood that the leveling screws 37 and cooperating elements are for the purpose of adjusting, to a vertical position, the axis of the 10 sleeve 33 in conditioning the instrument for operation of the sighting device.

In the embodiment comprising a transit, as shown in Figures 1 and 2 of the drawings, the sleeve 33 comprises a journal which rotatably receives and supports a sleeve-like element 51 comprising a clamp mounting frame, which, in turn, rotatably receives and supports a spindle 53 so that the spindle 53, sleeve 51, and journal 33 have coaxial concentric relationship and are each 20 relatively rotatable with respect to the other. The spindle, sleeve and journal also are preferably tapered, so that the parts may be held in assembled relationship, as by means of the holding nut 55 applied on the projecting end of the 25 spindle in position riding upon the lower ends of the sleeve and journal.

The lower end of the journal is preferably threaded to receive a spherical nut 57 and holding means comprising a nut 59. The spherical 30 nut 57 comprises a part of the ball and socket connection 29, the other part of which comprises a member 61 having a dome-like portion forming a shell receiving the nuts 57 and 59, and a plate-like portion secured to the base 27. The 35 nut 59, at its periphery, carries a resilient sealing gasket 63 in position wiping upon the inner surfaces of the dome 61 to seal the ball and socket connection against access by deleterious foreign material.

40 The journal 33 also is threaded to receive an annular skirt 65 preferably of sheet-metal and having curled marginal edges enclosing an annular sealing gasket 67 adapted to wipe upon the outer surfaces of the dome 61 to prevent deleterious 45 foreign matter from reaching the ball and socket connection through the opening in the top of the dome through which the journal 33 extends.

The upper end of the sleeve 51 projects upwardly of the journal 33 and is provided with a 50 head 69 which overlies the upper end of the journal 33, the outer surfaces of the upper end of which provide cylindrical surfaces. The head 69 is formed with a seat receiving a collar 71 which 55 is secured in place on the head in any suitable manner, as by fastening screws 73. The collar 71 has an annular flanged portion 77, the peripheral edges of which are preferably beveled, as illustrated. This collar 71 has a cylindrical portion 75 snugly embracing the outer cylindrical portions of the upper end of the journal 33, the outer end of said portion 75 riding on an upwardly-facing, annular shoulder or seat 79 formed in the outer surfaces of the journal 33, 60 said shoulder being extended outwardly of the lower edge of the portion 75 in position facing the under side of the flange 77.

The head 69 also provides an annular, downwardly-facing seat or shoulder 81 which faces 70 the upper surface of the flange 77, and has a cylindrical surface 83 forming an annular seat in the head adjacent the shoulder 81 and between it and the facing surface of the flange 77. The collar 71 likewise forms a cylindrical seat 85 in 75 the outer surfaces of the portion 75 and extend-

ing between the shoulder 79 and the facing surface of the flange 77.

The spindle 53 has a head 89 extending outwardly of and above the upper end of the sleeve 51. On this head is mounted and secured, as by means of the fastening screws 91, a compass plate 93 having a dependent marginal flange 95 and carrying a compass 97 enclosed in a casing mounted on the plate.

The compass comprises a compass ring 99, concentric with respect to the axis of the spindle, and an indicator element 101 pivoted, as at 103, for rotation about the axis of the spindle. The compass also preferably includes operable mechanism, indicated at 105, comprising a stem extending in a sleeve-like frame portion 104 and provided with a manually-operable head 106 on said sleeve-like portion for selectively disabling the pointer element and conditioning it for operation, and also for adjustably turning the index ring 99. 20

The head 69 of the sleeve element 51 is provided upwardly of the shoulder 81 with an annular seat 107 adapted to receive and support an annular cover plate 109 which is anchored at its inner portions on the seat 107 in any suitable fashion, as by the fastening elements 111. The cover plate 109 extends outwardly of the seat 107 and underlies the compass plate 93. It has an upwardly extending flange 113 extending within and bearing upon the marginal flange 95 30 of the compass plate.

A resilient annular gasket 115 is preferably interposed between the flanges 95 and 113 in order to seal the space therebetween, the gasket preferably being received in a peripheral groove 35 formed in the flange 113. The flange 113 also is formed to provide an upwardly-facing scale surface 113 visible upwardly of the compass plate through suitable openings provided therein. These openings may be hidden by suitable covers 40 119 adapted to be lifted to the position illustrated in Figure 1, when it is desired to view the scale surfaces 117. The plate 109 may be accurately adjusted on the frame 69 by means of the aligning screws 112 disposed radially and in spaced relationship in the seat 107 to make flange 113 exactly concentric with the axis of the sleeve 51. 45

The compass plate may also carry one or more liquid levels 121 in order to adjust the same in horizontal position in conditioning the transit 50

The compass plate also carries a frame comprising spaced uprights 123 which are provided with journals, as at 125, in which is mounted a tilting frame or axle 127 on which the sighting device or telescope is carried. One of the frame elements and the axle may be provided with cooperating scale means preferably enclosed by a guard 129, said cooperating scale means being adapted to indicate the tilted condition of 55 the telescope with respect to the compass plate.

It will be noted that the frame element comprising the sleeve 51 is freely rotatable with respect to the support frame 31; that the frame comprising the spindle and the compass plate is 60 freely rotatable with respect to the sleeve element 51 and the parts mounted thereon; and that the sighting device is freely rotatable and tiltable with respect to the compass plate and its supporting frame. The parts may thus be freely 65 adjusted with respect to each other.

In using the transit, however, it is necessary to clamp or anchor the various parts in relatively adjusted position and also to provide means for relatively turning the same by slight 70 75

amounts and accurately in order to precisely align the sighting device upon an objective, and to this end tangent clamps are employed, there being a clamp 131 cooperatively associated with the tilting frame 127 and the supports carrying the same from the compass plate, a clamp 133 cooperatively associated with the compass plate and the clamp mounting sleeve element or frame 51, and a clamp 135 cooperatively associated with the clamp-carrying frame 51 and the leveling frame 31.

These clamps 131, 133 and 135 are preferably of like construction, the same being illustrated, respectively, in Figures 3, 4 and 5 of the drawings.

In the level illustrated in Figure 13, the same comprising a so-called Y level, the sighting device or telescope 25 is secured in a frame, preferably comprising an elongated plate 139 carrying telescope supports 141. The frame 139 is provided with a spindle similar to the spindle 53 in the embodiment illustrated in Figure 2, which spindle is journalled directly in the sleeve-like portion 33 of the leveling frame 31. The frame 139 is thus freely rotatable with respect to the support frame 31 in order to orient the sighting device about the axis of the sleeve 33. To secure the frame 139 in the sleeve, and at the same time to provide for accurately adjusting the relative angularity of the parts, a tangent clamp 137 is provided, said clamp preferably having a construction and arrangement similar to that of the clamps 131, 133 and 135 in the transit embodiment.

The clamps 131, 133, 135 and 137 comprise frames, each providing an annular clamping portion 143, and tangent adjusting means 145 in spaced relationship with respect to the annular clamping portion, the parts being interconnected to form a preferably integral structure. The inner surfaces of the clamping portions 143 in each instance are formed for reception in a corresponding clamp seat, and the opposed side surfaces of the clamping portions are provided each with an annular sealing gasket 147 preferably comprising a felt gasket extending in a suitable groove formed in the face of the clamping portion.

The inner surface of the clamping portion is also preferably cut away, as at 149, to form a preferably semicylindrical seat for a clamping element 151, comprising a clamping block having semicylindrical surfaces adapted to extend in the seat 149, and a clamping surface which may be conveniently formed to continue the curvature of the inner surface of the clamping portion.

Opposite the seat 149 the clamping portion 143 is formed with an outstanding sleeve 153 which contains a block connected stem 155, and I provide means for actuating the stem 155 and its connected clamping block from the outer end of the sleeve-like extension 153. To this end, the inner surfaces of the sleeve, at least the outer portions thereof, are threaded to receive a screw-threaded element 157, which may be an extension of the stem 155 or may be separately formed, the outer end of which projects from the end of the sleeve and is formed for connection with a manually-operable head 159.

In the illustrated embodiment the outer end of the threaded element 157 has a fluted or ridged configuration and is adapted to receive the head 159 shrink-fitted thereon.

By operating the head, the threaded member

157 may be tightened into the sleeve, thereby forcing the stem 155 and the clamping block 151 radially inwardly in order to clampingly engage and secure the portion 153 on a clamp seat on which it is assembled.

I prefer to form the threaded member 157 as an element separate from the stem 155 in order that the same may be readily renewed in the event of damage. Projecting elements of this character often become bent in service due to forces accidentally applied on the head 159 in a direction to cause bending of the projecting portions of the element 157. In order to minimize such mechanical damage to the projecting screw portions, and also to improve the appearance of the instrument, and to house the projecting screw portions and protect the same from the deleterious effect of foreign matter, such as atmospheric dirt and moisture, I prefer to form the head 159 to a generally tear-drop configuration, and to form the head with a cylindrical socket 161 of appreciable depth around the screw-threaded element 157.

This socket 161 is formed to snugly receive the cylindrical end portions of the sleeve-like frame extension 153, so that the head 159 is substantially journalled on and supported by the outer surfaces of the sleeve. By means of this arrangement, screw bending forces applied on the head are largely absorbed by the extension 153, so that the screw itself is protected against damage through bending. The tear-drop configuration of the head permits accidental blows to glance off, thus additionally protecting the screw against damage. A similar arrangement may be employed for supporting the stem head 106 on its supporting sleeve 104.

As shown in Figures 3 and 5, the sleeve 153 may extend outwardly of the clamp portion 143 in any desired or convenient direction. In Figure 4 of the drawings, however, I have shown the sleeve 153 extending between the clamping portion 143 and the tangent adjusting means 145, so that the sleeve extension 153 not only serves to support and enclose the clamp actuating stem and screw 155 and 157 and support the actuating head 159, but also serves to brace and strengthen the clamp frame and to assist in rigidly interconnecting the clamping portion 153 with the adjusting mechanism 145.

The clamp 131, shown in Figure 3 of the drawings, is assembled in the transit on the tilting frame 127, with the portion 143 of the clamp mounted on a cylindrical clamp seat concentric with the tilting axis of the frame 127, the clamping portion 143 of the clamp being received between facing shoulders 163 formed adjacent and on opposite sides of the cylindrical clamp seat.

The clamp 133 in the transit assembly is mounted with the clamping portion 143 embracing the clamp seat 83, the opposite sides of the clamp portion, respectively, engaging the shoulder 81 and the facing surface of the flange 77.

The clamp 135 in the transit assembly is mounted with its clamping portion 143 embracing the clamp seat 85, with the opposite sides of the clamp portion 143 extending between and respectively engaging the shoulder 79 and the facing surface of the flange 77.

The clamp 137 of the level is assembled with its clamping portion 143 embracing a cylindrical clamp seat formed in the upper end of the sleeve 33, with the opposite sides of the clamp portion bearing upon facing shoulders formed, respectively, in the frame 139 and in the sleeve 33.

In each clamp the packing means 137 serves to seal the sliding joint between the clamp portion 143 and the facing shoulders defining the opposite sides of the clamp seat, to protect the 5 clamp surfaces from deleterious foreign matter.

The tangent adjusting mechanism in each case comprises cooperating means 145 and 146, respectively, on a pair of relatively angularly movable frames. The cooperating means 145 on one frame 10 comprises a preferably elongated housing 171, in the opposite ends of which are mounted tangent adjusting pintles having ends extending oppositely into the interior of the housing. To this end, the pindle supporting housing comprises a pair of 15 spaced apart sleeve portions 173 and 175 in coaxial alignment, with a space 177 between the facing ends of the sleeves. The outer end of the sleeve 173 in each case carries a cover 179 comprising a shell closed at one end, the opposite 20 end being open and threaded into the outer end of the sleeve 173. The shell and sleeve on which it is mounted slidably receive a pindle element 181 having an end extending into the space 177.

The pindle element 181 is preferably hollow 25 and fits snugly into the sleeve 173 to form therewith and with the shell 179 a closed, expansible housing containing spring means 183 normally urging the pindle element in a direction toward and into the space 177.

30 It will be seen that the foregoing arrangement substantially prevents the entrance of deleterious foreign matter into the expansible housing enclosing the spring 183 which is thus protected against deterioration by the cooperation of the 35 pindle and the shell.

The sleeve 175 is internally threaded to receive a threaded stem 185 having a pointed end extending within the space 177 in opposing alignment with respect to the pindle 181. The stem 40 185 extends at its opposite end outwardly of the sleeve 175 and is provided with a manually-operable head 187 preferably similar to the head 159, the outer end of the stem 185 being fluted and receiving the head shrink-fitted thereon.

45 The outer surfaces of the end of the sleeve 175 are preferably finished to cylindrical form, and the head 187 is provided with a cavity 189 to snugly receive the end of the sleeve in order to substantially journal and support the head on the sleeve in order to enclose and protect the stem against bending and against deleterious foreign matter, as heretofore described in connection with the head 159.

The sleeve 175 may be slit longitudinally, as at 55 191, the split portions being interconnected by a clamping element 193 for adjusting the tightness of the sleeve upon the stem 185. The housing 171 is provided with a lateral opening 195 between the facing ends of the sleeves 173 and 60 175, said opening giving access to the chamber 177 and being defined by edges forming a seat.

The housing 171 and the adjusting pintles mounted therein are supported on one of a pair of relatively movable frame elements, which, in 65 the embodiments illustrated in Figures 1, 2 and 13, is preferably the frame element having the clamp means 143. Another of said relatively movable frame elements, which, in all of the illustrated embodiments, comprises the frame 70 which is rotatable with respect to the one on which the clamping frame is adjustably mounted, carries the cooperating tangent adjustment means 146 which comprises an extension forming a cover 165 comprising a seat adapted at all 75 times to overlie and form a cover for the opening

195. The housing 171 also is preferably formed with a groove at the opening 195 in which is mounted a sealing gasket 197 in position to wipe upon the cover or seat 165 and securely seal the opening 195.

As shown in Figures 1-9 and 11-14, each of the clamps 131, 133, 135 and 137 have frame portions extending outwardly of their respective clamping portions 143 and preferably carry the tangent adjusting means 145 in position opposite the cover 10 165 which is formed in a frame element associated with and angularly movable with respect to the carrying frame on which the clamp is seated. In connection with the clamp 131, the cover 165 is formed on one of the uprights 123. In connection with the clamp 133, the cooperating cover 165 is formed in an extension 167 on and preferably integral with the compass plate 93 at the marginal edge thereof. In connection with the clamp 135, the cooperating cover 165 is formed in an extension 169 on and preferably integral with the tilting frame 31. In connection with the clamp 137, the cooperating cover 165 is formed on the lower surface of the telescope-carrying frame 15 139.

The extension forming the cover or seat 165 also carries a finger 199 extending outwardly of the seat 165 in position to enter the cavity or chamber 177 between the facing ends of the aligned tangent adjusting members 181 and 185. 30 This finger preferably has a hardened insert 201 upon which the opposite ends of the adjusting elements are adapted to bear. The finger 199 is mounted in the seat-forming element in any suitable or preferred manner, preferably by 35 threading the finger in a correspondingly threaded socket arranged in the seat-forming element.

In the embodiments illustrated in Figures 1-9 and 11-14, the housing 171 is formed as an integral part of the clamp frame, so that the 40 tangent adjusting pintles 181 and 185 are mounted on the clamp, while the finger 199 is carried in a relatively movable frame portion. My invention, however, contemplates and includes a reversal of the cooperating tangent adjusting 45 elements wherein the finger 199 is mounted on and the seat 165 is formed in the clamp, while the housing 171, in which the adjusting pintles are mounted, is attached to the cooperating angularly movable frame element; that is to say, 50 the frame member which is rotatable with respect to the carrying frame on which the clamp frame is adjustably supported. This possibility is shown in Figure 10 in which cooperating means 145, comprising the housing and the pintles 55 mounted therein, is attached to the compass plate, as shown at 203, the housing being preferably formed as an integral extension on the compass plate at the marginal edge thereof, while the cooperating compass plate clamp member is 60 formed, as shown at 205, with the cooperating means 146 comprising the cover for covering the lateral housing opening and the finger 199. In this embodiment the clamp is of simplified construction, the extension 153 which carries the 65 clamp-actuating stem serving also as a support for the cover-forming extension and for the finger 199.

In Figures 11 and 12 of the drawings, I have shown a modified arrangement of the clamp 133 70 whereon the housing 171 is arranged with the housing opening facing in a direction radially away from the axis of the clamping portion 143, as distinguished from the housing arrangements in which the housing opening faces a direction 75

parallel with respect to the axis of the clamp portion 143, in which the seat 165 may lie in a flat plane, the edges of the housing opening likewise extending in a flat plane.

5. In the embodiment shown in Figures 11 and 12, however, the seat 165 is necessarily curved about a center of curvature coinciding with the axis of the clamp portion 143, and the edges defining the housing opening 195 are correspondingly curved 10 in order to maintain a tight seal at the opening 195.

It will be seen, from the foregoing, that the tangent adjusting mechanism, including the operating ends of the pintles 181 and 185, as well as 15 the finger 199, are at all times sealed within the chamber 177, so that atmospheric dirt, moisture and other deleterious substances are excluded, and deterioration of the accurate adjusting mechanism is prevented. The arrangement of 20 the housing as an integral part of the frame on which it is mounted not only imparts strength and rigidity to the frame and particularly where the housing forms a part of a clamp frame, but the housing itself interconnects and rigidifies the 25 sleeves in which the tangent adjusting pintles are mounted, so that the pintles are protected against mechanical damage, as well as from displacement and resulting misalignment, the parts being especially well protected against mechanical 30 damage resulting from blows and impact to which devices of the character mentioned are frequently exposed when in service.

Not only is the relatively delicate tangent adjusting mechanism entirely housed and protected 35 from deleterious matter and mechanical damage, but the clamps also are rigidified. In addition, the arrangement of the clamp seats, particularly as shown in Figure 2 of the drawings, wherein the clamps are provided with the sealing 40 gaskets 147 in position to cooperate with the flange 11 and with the shoulders 79 and 81, insures exclusion of deleterious dirt and moisture from the bearings and journals by means of which the relatively rotatable parts are connected 45 together, said parts being protected against entrance of foreign matter through the lower end thereof by means of the nut 55. So, also, the sealing gaskets 147 in the clamp 131 prevent foreign matter from reaching and impairing the 50 interior bearing surfaces of the clamp and the seat on which it is mounted.

It is thought that the invention and numerous of its attendant advantages will be understood from the foregoing description, and it is obvious 55 that numerous changes may be made in the form, construction and arrangement of the several parts without departing from the spirit or scope of the invention, or sacrificing any of its attendant advantages, the form herein described being a 60 preferred embodiment for the purpose of illustrating the invention.

The invention is hereby claimed as follows:

1. In a device of the class described, in combination, a pair of relatively shiftable frame 65 members, means forming a housing on one of said members having an opening defined by edges forming a cover seat about said opening, means forming an abutment on the other of said members and a cover surrounding said abutment and 70 having a surface in position to slidably engage said seat, whereby the means forming said cover and said housing may cooperate to provide an enclosure for said abutment, and adjusting means on the housing in position to cooperate with said 75 abutment within the housing to relatively shift

the abutment therein whereby to accurately adjust the relative position of said members.

2. The combination stated in claim 1, including resilient gasket means interposed between the seat and cover. 5

3. The combination stated in claim 1, wherein the frame members are interconnected for relative angular movement about an axis and wherein the surface of the cover is curved with center of curvature at said axis, the cover seat being 10 correspondingly curved.

4. The combination as set forth in claim 1, wherein said adjusting means comprises a stem having an end projecting from a sleeve-like portion of said housing having an annular surface 15 forming a seat encircling said stem, and a head on the projecting portions of said stem and formed with a skirt encircling said projecting portions and having an annular surface interfitting with the annular surface of the sleeve-like portion to provide support for said head directly on the sleeve-like portion to prevent stem-bending movement of the head with respect to the sleeve-like frame portion. 20

5. In a device of the class described, a frame 25 having a sleeve-like stem supporting portion, a stem supported in and having a portion projecting from an end of said sleeve-like portion, said sleeve-like portion having an outwardly-facing cylindrical seat formed on the end thereof 30 in position concentric with respect to the axis of said supported stem, and an operating head on the projecting portions of said stem, said head having a skirt enclosing said projecting portions and having an inwardly-facing, annular surface 35 snugly enclosing the cylindrical surfaces of the sleeve-like portion to provide support for said head directly on the sleeve-like portion to prevent stem-bending movement of the head with respect to the sleeve-like frame portion. 40

6. In a device of the class described, in combination, a pair of relatively shiftable frame members, means forming a housing on one of said members having an opening defined by edges forming a cover seat about said opening, 45 means forming an abutment having oppositely facing shoulders on the other of said members and a cover surrounding said abutment and having a surface in position to slidably engage said seat, whereby the means forming said cover and said housing may cooperate to provide an enclosure 50 for said abutment, and adjusting means comprising aligned pintles on the housing and having facing ends in position to engage said oppositely-facing shoulders of the abutment within the 55 housing, said pintles being operable to relatively shift said abutment within said housing whereby to accurately adjust the relative position of said members.

7. In a device of the class described, in combination, a pair of relatively shiftable frame members and a mounting member, means forming a housing on one of said frame members having an opening defined by edges forming a cover seat about said opening, means forming an 65 abutment on the other of said frame members and a cover surrounding said abutment and having a surface in position to slidably engage said seat, whereby the means forming said cover and said housing may cooperate to provide an enclosure 70 for said abutment, cooperating means on one of said frame members and on the mounting member comprising means forming a clamp seat on the mounting member and clamp means on the frame member operable to adjustably secure 75

the frame member on said mounting member, and adjusting means on the housing in position to cooperate with said abutment within the housing and operable to accurately adjust the relative position of said frame members.

8. In a device of the class described, in combination, a pair of relatively shiftable frame members and a mounting member, means forming a housing on one of said frame members having an opening defined by edges forming a cover seat about said opening, means forming an abutment on the other of said frame members and a cover surrounding said abutment and having a surface in position to slidably engage said seat, whereby the means forming said cover and said housing may cooperate to provide an enclosure for said abutment, cooperating means on one of said frame members and on the mounting member comprising means forming a clamp seat on the mounting member and clamp means on the frame member operable to adjustably secure the frame member on said mounting member, and adjusting means comprising a pintle threaded in and having an end extending within said housing in position to engage said abutment therein and means extending outwardly of said housing to actuate said pintle to move said abutment relatively and within said housing whereby to adjust the relative position of said frame members.

9. In a device of the class described, in combination, a pair of relatively shiftable frame members and a mounting member, means forming a housing on one of said frame members having an opening defined by edges forming a cover seat about said opening, means forming an abutment on one of said frame members and a cover surrounding said abutment and having a surface in position to slidably engage said seat, whereby the means forming said cover and said housing may cooperate to provide a closure for said abutment, cooperating means on one of said frame members and on the mounting member and comprising means forming a clamp seat on the member and clamp means on the frame member operable to adjustably secure the frame member on said mounting member, and adjusting means on the housing in position to cooperate with said abutment within the housing and operable to accurately adjust the relative position of said frame members, and manually-operable means for actuating said clamp means and said adjusting means and comprising stems having manually-operable heads positioned in adjacent relationship in the assembly to facilitate operation of both heads from a common manipulative position.

10. In a device of the class described, in combination, a pair of relatively shiftable frame members and a mounting member, means forming a housing on one of said frame members having an opening defined by edges forming a cover seat about said opening, means forming an abutment on one of said frame members and a cover surrounding said abutment and having a surface in position to slidably engage said seat around said abutment whereby the means forming said cover and said housing may cooperate to provide a closure for said abutment, cooperating means on one of said frame members and on the mounting member and comprising means forming a clamp seat on the mounting member and clamp means on the frame member operable to adjustably secure the frame member on said mounting member, adjusting means on the hous-

ing in position to cooperate with said abutment within the housing and operable to accurately adjust the relative position of said frame members, manually-operable means comprising a clamp actuating stem carried, in the frame member having the clamp means and extending therein, substantially adjacent said abutment, and additional manually-operable means comprising an adjusting screw extending, in the frame member carrying said housing, in a direction substantially at right angles with respect to the clamp screw.

11. In a device of the class described, in combination, a pair of relatively shiftable frame members and a mounting member, means forming a housing on one of said frame members having an opening defined by edges forming a cover seat about said opening, means forming an abutment on the other of said frame members and a cover surrounding said abutment and having a surface in position to slidably engage said seat, whereby the means forming said cover and said housing may cooperate to provide an enclosure for said abutment, cooperating means on the frame member having the housing and on the mounting member comprising means forming a clamp seat on the mounting member and clamp means on the frame member operable to adjustably secure the frame member on said mounting member, manually-operable means for actuating the clamp means comprising a stem supported in said frame and having a manually-operable head adjacent said housing, and adjusting means carried by the housing in position to cooperate with said abutment within the housing and comprising a stem having a headed end extending outwardly of said housing in a direction substantially normal to the clamp actuating stem.

12. In a device of the class described, in combination, a pair of relatively shiftable frame members and a mounting member, means forming a housing on one of said frame members having an opening defined by edges forming a cover seat, means forming an abutment on the other frame member and a cover surrounding said abutment in position to slidably engage said seat, whereby said cover and said housing cooperate to provide an enclosure for said abutment, cooperating means on the frame member having the abutment and cover and on the mounting member comprising means forming a clamp seat on the mounting member and clamp means on the frame member operable adjustably to secure the frame member on said mounting member, said clamp means comprising a clamp actuating stem supported in the frame member and extending in alignment with said abutment, said stem having an end projecting from said frame member beyond and adjacent said abutment and its enclosing housing, a manually-operable head on the projecting end of said stem, adjusting means on the housing in position to cooperate with said abutment therein and comprising a stem having an end projecting from said housing and provided with a manually-operable head adjacent the head on said clamp actuating stem.

13. In a device of the class described, in combination, a pair of relatively shiftable frame members and a mounting member, means forming a housing on one of said frame members having an opening defined by edges forming a cover seat about said opening, means forming an abutment on one of said frame members and a cover surrounding said abutment and having a surface in position to slidably engage said seat, whereby

the means forming said cover and said housing may cooperate to provide a closure for said abutment, cooperating means on one of said frame members and on the mounting member and comprising means forming a clamp seat on the member and clamp means on the frame member operable to adjustably secure the frame member on said mounting member, and adjusting means on the housing in position to cooperate with said abutment within the housing and operable to accurately adjust the relative position of said frame members, and manually-operable means for actuating said clamp means and said adjusting means and comprising stems each extending in and having an end projecting from a sleeve-like frame portion, said sleeve-like portion having an annular surface forming a seat encircling the stem therein, and a head on the projecting portion of the stem and formed with a skirt enclosing said projecting portion and having an annular surface interfitting with the annular surface of the sleeve-like frame portion to provide support for said head directly on the frame portion to prevent stem-bending movement of the head with respect to the frame portion.

14. In a surveying instrument, in combination, a mounting member, a pair of frame members mounted for relative angular movement with respect to said mounting member about a common axis, cooperating adjusting means comprising means forming a housing on one of said frame members having an opening defined by edges forming a cover seat about said opening, means forming an abutment on said other frame member and a cover surrounding said abutment and forming a surface adapted to slidably engage said peripheral seat, whereby the means forming said cover and said housing may cooperate to provide an enclosure for said abutment, cooperating means on one of said frame members and on the mounting member comprising means forming a clamp seat on the mounting member and clamp means on the frame member operable to adjustably secure the frame member on said mounting member, adjusting means on the housing in position to cooperate with said abutment to adjustably shift the same within the housing whereby to accurately adjust the relative angular position of said frame members, and means for supporting a sighting device on one of said members.

15. A surveying instrument as set forth in claim 14, wherein one of said frame members comprises a base forming a journal and associated means for leveling said base, while the mounting member comprises a clamp carrying frame having a sleeve rotatable in said journal with an end projecting therefrom and formed with a pair of adjacent clamp seats defined between shoulders formed on said frames, the other of said frame members comprising a clamp frame embodying the clamp means and mounted in clamping relationship on one of said clamp seats formed in said clamp-carrying frame between shoulders, respectively, on the base and on the clamp-carrying frame, said adjusting means being cooperatively associated with said base and clamp frame, the means for supporting said sighting device comprising a support frame having a portion journalled for rotation in said sleeve, and an additional clamp frame having a clamping portion on the other of said clamp seats between shoulders formed on the clamp-carrying frame, cooperating means on said additional clamp and support frames comprising an abutment on one

and a housing on the other enclosing said abutment, and means mounted on the housing for shifting the abutment therein whereby to angularly adjust the additional clamp and support frames, and resilient gasket means on the opposed sides of the clamping portions of said clamp frames for sealing the joints made by said portions with the shoulders defining said clamp seats.

16. A surveying instrument as set forth in claim 14, wherein one of said frame members comprises a plate having an annular, peripheral dependent flange and having an axle journalled in the mounting member, and wherein the means for supporting said sighting device is carried on said plate, said mounting member, in addition to the clamp seat, carrying means forming an annular seat between the clamp seat and said plate, an annular cover member sealed on said seat and having peripheral edges extending to and interfitting with the peripheral flange of said plate, and a packing material interposed between said interfitting marginal flanges.

17. A surveying instrument as set forth in claim 14, wherein one of said members comprises a support frame or base and another of the members comprises a carrying frame formed to support means for mounting a sighting device on the carrying frame, the frame member having the clamp means serving to adjustably secure the support frame and carrying frame in a desired relative angular relationship, and means for leveling the support frame or base.

18. In a surveying instrument, comprising a support and instrument carrying means rotatable on the support, the combination with said support and said carrying means of projecting means on said support and extending to an edge of said carrying means, tangent adjusting means on said support in position to operatively engage said projecting means, said carrying means being formed at its edge with an integral lateral extension comprising a downwardly curled lip and aligned sleeve-like portions at opposite ends of and integral with said lip, said projecting means comprising a finger portion extending within said lip and between the facing ends of said sleeves and the tangent adjusting means comprising pintles in said sleeve-like portions and having ends engaging upon opposite sides of said finger.

19. In a surveying instrument, a support element and a carrying element for a sighting device pivoted for relative angular movement about a common axis, a clamp element having an annular part encircling one of said relatively pivoted elements whereby the clamp is relatively and angularly adjustable with respect to the element on which it is mounted on said common axis, means manually operable to clamp said annular part in adjusted angular position with respect to said element, said clamp having integral projecting portions carried by and extending from said annular part opposite a remote portion of the other relatively pivoted element, a projecting finger integral with one of said portions, said other portion having integral means forming aligned sleeves having facing ends in spaced abutting relationship, said integral means including a lip laterally enclosing the sides of the space between the abutting ends of the sleeves to form a compartment in which said finger extends between the abutting ends of the sleeves, and tangent adjusting means comprising pintles in said sleeves and having ends extending in said compartment in position to engage opposite sides of said finger, one of said pintles being screw-

threaded in its corresponding sleeve and projecting outwardly of the end of said sleeve opposite from the chamber and formed with manually operable means on its outwardly projecting portions 5 for adjusting its position in the sleeve, and the other pintle being yieldingly pressed toward and into engagement with said finger to keep the finger in yielding engagement with the threaded pintle.

10 20. In a surveying instrument as set forth in claim 19, the combination wherein the projecting finger is formed with integral means in position to slidingly cooperate with said lip to close the chamber regardless of the relative position 15 of the finger within the chamber and between the facing ends of said sleeves.

21. In a surveying instrument as set forth in claim 19, the combination wherein said lip encloses at least three sides of the space between 20 the abutting ends of the sleeves, and forms a trough for simultaneously receiving the finger in all of its adjusted positions between the facing ends of the sleeves.

22. In a surveying instrument as set forth in claim 19, the combination wherein the manually operable means for clamping the annular part of the clamp upon the element upon which it is mounted comprises a stem threaded in said clamp and extending from the annular part 30 thereof in a channel formed in the projecting portion of the clamp, said stem having an end extending outwardly of the end of said projecting portion adjacent the remote portion of the other relatively pivoted element and formed with 35 manually operable means on its outwardly extending end for controlling the clamp whereby said manually operable clamp controlling means is disposed adjacent the manually operable tangent adjusting means.

40 23. In a surveying instrument as set forth in claim 19, the combination wherein the projecting portions of said clamp comprise a pair of spaced arms extending outwardly of said annular part, each of said arms terminating in one of said 45 alined sleeves whereby said clamp is constituted as a rigid, rugged frame carrying not only the manually operable clamp means but also the tangent adjusting means, including the alined sleeves carrying the pintles as well as the integral lip interconnecting said sleeves and forming the finger receiving trough or chamber.

24. In a surveying instrument comprising a support, a rotatable compass plate on said support, a rotatable compass plate on said support and having integral means at the peripheral 55 portions of said plate forming a dependent lip and aligned sleeves at the opposed ends of said lip, means on said support including a finger extending between the opposed ends of said sleeves, and pintles carried by said sleeves and 60 having ends extending therefrom within said lip in position to engage the opposed sides of said finger, at least one of said pintles being longitudinally adjustable in its sleeve to determine the relative angularity of the plate with respect 65 to said finger.

25. In a surveying instrument comprising a support and instrument-carrying means rotatable on the support, the combination with said support and said carrying means of a clamp comprising an annular portion encircling said instrument-carrying means, means to secure said annular portion fast on said instrument-carrying means, said annular portion having a pair of integral arms extending outwardly thereof, the 70 ends of said arms being formed with integral 75

sleeve-like portions in axial alignment, said support being formed with a finger extending between the facing ends of said sleeve-like portions, integral means rigidly interconnecting said sleeve-like portions and forming a housing enclosing said finger, and pintles carried by each sleeve and having ends extending therefrom within said housing and in position to engage opposed sides of said finger. 5

26. In a surveying instrument comprising a support standard and an instrument-carrying axle rotatable on said standard, the combination with said standard and said carrying axle, of a clamp comprising an annular portion encircling said axle, means to secure said annular portion fast on said axle, said annular portion having a pair of integral arms extending outwardly thereof tangentially, the ends of said arms being formed with integral sleeve-like portions in axial alignment, said standard being 20 formed with an outstanding finger extending between the facing ends of said sleeve-like portions, integral means rigidly interconnecting said sleeve-like portions and forming a trough-like housing enclosing said finger, and pintles carried by each sleeve and having ends extending therefrom within said housing in position to engage opposite sides of said finger. 25

27. A surveying instrument as set forth in claim 14, wherein the member having the clamp 30 seat comprises a support frame or base and another of the members comprises a carrying frame formed to support means for mounting a sighting device on the carrying frame, the frame member having the clamp means serving to adjustably secure the support frame and carrying frame in a desired relative angular relationship, and means for leveling the support frame or base. 35

28. A surveying instrument as set forth in claim 14 wherein the member having the clamp 40 seat comprises a carrying frame formed to support means for mounting a sighting device on the carrying frame while another of the members comprises a support frame or base, the frame member having the clamp means serving to adjustably secure the support frame and carrying frame in a desired relative angular relationship, and means for leveling the support frame or base. 45

29. A surveying instrument as set forth in claim 14, wherein one of the members comprises 50 a carrying frame adapted to support means for mounting a sighting device, another of said members comprises a support frame or base in which the carrying frame is journaled for rotation, and wherein the means forming the abutment 55 enclosing housing is on the member having the clamp, the abutment and cover being on one of the other members.

30. A surveying instrument as set forth in claim 14, wherein one of the members comprises 60 a carrying frame adapted to support means for mounting a sighting device, another of said members comprises a support frame or base in which the carrying frame is journaled for rotation, and wherein the means forming the abutment enclosing housing is on the member having the clamp, the abutment and cover being on the carrying frame. 65

31. A surveying instrument as set forth in claim 14, wherein one of the members comprises 70 a carrying frame adapted to support means for mounting a sighting device, another of said members comprises a support frame or base in which the carrying frame is journaled for rotation, and wherein the means forming the abutment enclosing 75

ing housing is on the member having the clamp, the abutment and cover being on the support frame or base.

32. A surveying instrument as set forth in 5 claim 14, wherein one of the members comprises a carrying frame adapted to support means for mounting a sighting device, another of said members comprises a support frame or base in which the carrying frame is journalled for rotation, and 10 wherein the means forming the abutment and housing cover is on the frame member having the clamp, the abutment enclosing housing being on one of the other members.

33. A surveying instrument as set forth in 15 claim 14, wherein one of the members comprises a carrying frame adapted to support means for mounting a sighting device, another of said members comprises a support frame or base in which the carrying frame is journalled for rotation, and 20 wherein the means forming the abutment and housing cover is on the frame member having the clamp, the abutment enclosing housing being on the carrying frame.

34. A surveying instrument as set forth in 25 claim 14, wherein one of the members comprises a carrying frame adapted to support means for mounting a sighting device, another of said members comprises a support frame or base in which the carrying frame is journalled for rotation, and 30 wherein the means forming the abutment and housing cover is on the frame member having the clamp, the abutment enclosing housing being on the support frame or base.

35. A device of the class described comprising 35 a frame element formed with a bearing, a support member in said bearing, means mounting a sighting device for rotation with said support member, means on said member comprising a projecting element, means on one of said elements forming a chamber having an opening and the other element having a finger portion extending into the chamber through said opening and having a bearing portion disposed within the chamber, a stem threaded in a wall of said chamber at one end thereof in position to engage 40 one side of said bearing portion, means extending outwardly of said chamber and manually operable to turn said stem, means in the walls of said chamber at the opposite end thereof and 45 having a presser portion extending in said chamber on the opposite side of said bearing portion, and means yieldingly urging said presser portion toward the bearing portion whereby to hold the same in engagement with said stem so that by 50 adjusting the stem the relative angular position of said finger about the axis of said support member with respect to the element having the chamber may be critically adjusted.

36. A device of the class described, comprising

a pair of frame elements interconnected for relative rotational movement, one of the elements forming a support for the other, and said other element carrying means forming a mounting for a sighting device, and means to adjust the angular relationship of the elements comprising chamber forming means on one of said elements providing an enclosing chamber having a lateral opening, means on the other element comprising a finger in position extending in said chamber through said opening and having a bearing portion within said chamber, and adjusting means on said chamber-forming means and cooperatively associated with said bearing portion within the chamber for shifting said finger therein to 15 adjust the relative angular relationship of the said frame elements.

37. A device of the class described, comprising a pair of frame elements interconnected for relative rotational movement, one of the elements forming a support for the other, and said other element carrying means forming a mounting for a sighting device, spirit level means supported by 20 said mounting element, and means to adjust the angular relationship of the elements comprising chamber-forming means on one of said elements providing an enclosing chamber having a lateral opening, means on the other element comprising a finger in position extending in said chamber through said opening and having a bearing portion within said chamber, and adjusting means on said chamber-forming means and cooperatively associated with said bearing portion within 25 the chamber for shifting said finger therein to 30 adjust the relative angular relationship of the said frame elements.

38. A device of the class described, comprising a pair of frame elements interconnected for relative rotational movement, one of said elements supporting the other and said other element forming a mounting for a sighting device, and means to adjust the relative angular relationship of the elements comprising a clamp member and means to clamp the same on one of said elements, said clamp having an outwardly-extending portion, and the other element having 40 a cooperating portion adapted for cooperation with said extending portion, one of said portions comprising chamber-forming means providing a chamber having a lateral opening, and the other 45 portion comprising a finger in position extending in said chamber through said opening and having a bearing portion within said chamber, and adjusting means on said chamber-forming means and cooperatively associated with said bearing portion within the chamber for shifting said finger therein to 50 adjust the relative angular relationship of the said frame means.

ADOLPH LANGSNER.
